Inventor

John S. Williamson,
By Henry F. Brevington.

Attorney

UNITED STATES PATENT OFFICE.

JOHN S. WILLIAMSON, OF FOREST PARK, MARYLAND.

DOOR-OPERATING DEVICE.

1,253,448.

Specification of Letters Patent. Patented Jan. 15, 1918.

Application filed April 3, 1917. Serial No. 159,392.

To all whom it may concern:

Be it known that I, JOHN S. WILLIAMSON, a citizen of the United States, residing at Forest Park, in the county of Baltimore and State of Maryland, have invented certain new and useful Improvements in Door-Operating Devices, of which the following is a specification.

The mechanism which is the subject-matter of the present application for patent is designed more particularly for garages, stables and other buildings in which automobiles or other vehicles are stored, and it is the object of the invention to provide such building with a novel and improved door-operating means so constructed and arranged that the door is automatically opened as the vehicle approaches the doorway, thus obviating the necessity of the driver leaving the vehicle to open the door. The mechanism is also operable from the inside of the building, so that the door automatically opens to allow the vehicle to be driven out. The door is also automatically closed after the vehicle passes the same into or out of the building.

With the object stated in view, the invention consists in a combination and arrangement of parts to be hereinafter described and claimed, reference being had to the accompanying drawings forming a part of this specification.

In the drawings—

Figure 1 is a front elevation, partly in section, showing the application of the invention;

Fig. 2 is a sectional plan view thereof;

Fig. 3 is a longitudinal section of a tilttable valve actuating member;

Fig. 4 is a vertical section of a controlling valve;

Fig. 5 is a section on the line 5—5 of Fig. 4;

Fig. 6 is a section on the line 6—6 of Fig. 5;

Fig. 7 is an elevation, partly in section, of a latch mechanism, and

Fig. 8 is a plan view showing the invention applied to a swinging door.

Referring specifically to the drawings, 10 denotes a fragment of a garage or other building in which an automobile or other vehicle is stored. The vehicle enters the building through a doorway 11 provided with a pair of oppositely traveling, sliding doors 12. A fluid pressure apparatus is

provided for operating the doors, said apparatus comprising the following parts:

Above the doors 12 is supported, in any suitable manner, a cylinder 13 extending 60 parallel to the line of travel of the doors, and containing a pair of oppositely traveling pistons 14. Each piston has a rod 15, and the rod of one piston extends from one end of the cylinder and is suitably connected 65 to one of the doors, whereas the rod of the other piston extends from the other end of the cylinder and is connected to the other door. Thus, it will be seen that when the pistons travel outward toward the 70 respective cylinder ends, the two doors are slid open, and when the pistons travel inwardly toward each other the doors are slid closed. Fluid pressure, from any suitable source, enters the cylinder midway between 75 the ends, the inlet being shown at 16. The fluid pressure is also let into the cylinder adjacent each end at 17. When the fluid pressure is let into the cylinder between the pistons, the latter are forced outward to 80 open the doors, and upon admitting fluid pressure at the ends of the cylinder the pistons are forced inward to close the doors.

In the approach to the doorway 11 is mounted a vehicle-actuated valve mechanism whereby the admission of fluid pressure to the cylinder 13 is controlled. This mechanism comprises the following parts:

A housing 18 is embedded in the floor or roadway of the approach to the doorway 90 11. This housing is closed at the top by a tilttable platform 19 pivoted intermediate its ends to a suitable support 20 mounted in the housing. The platform is positioned transversely of the approach to the doorway and it is backed at its ends by springs 21 mounted in the housing, these springs serving to normally hold the platform level and flush with the top of the housing and to restore it to this position after it has 100 been depressed and the vehicle passes off of the same. The platform is positioned at the middle of the doorway approach, and the width of the doorway and the approach is such that the vehicle may be driven over one 105 end of the platform to depress this end upon entering the building, and over the other end to depress this end when leaving the building. The platform is therefore tilttable in two directions, which is for a purpose to be presently described.

In the housing 18 is mounted a valve cas-

- ing 22 having a fluid pressure inlet 23 at one end, and side outlets 24 and 25 for the fluid pressure. The inlet 23 is connected to the fluid pressure source. The outlet 24 is connected to the cylinder inlet 16, the connection being made by a pipe 26. A pipe 27 leads from the outlet 25 and has branches 28 connected, respectively, to the end inlets 17 of the cylinder 13.
- 10 In the casing 22 is located a slide valve 29 having a stem 30 which is suitably connected to the platform 19, as shown at 31 in Fig. 3, so that the valve is operated when the platform is tilted. The valve has an 15 exhaust duct 32 adapted to establish communication between the outlet ports 24 and 25, and an exhaust port 33 in the casing 22.
- The operation of the apparatus may be summarized as follows:
- 20 The platform 19 is normally level as shown in Fig. 3, in which position of the platform the valve 29 is in neutral position, both ports 24 and 25 being covered so that the fluid pressure is shut off from the cylinder 13. When the vehicle approaches the doorway 11 on the right, as shown dotted in Fig. 2, the wheels pass over the corresponding end of the platform 19 and depress this end, whereupon the valve 29 is pushed 25 down in the casing 22 to uncover the port 24 and to place the duct 32 in communication with the ports 25 and 33. The fluid pressure entering the casing 22 now passes out of the same through the port 24 and travels through 30 the pipe 26 to the cylinder inlet 16 and is thus admitted to the cylinder 13 between the pistons 14, whereupon they are forced outward and the doors 12 are slid open. Any pressure between the pistons and the cylinder 35 ends escapes through the pipes 28 and 27, the port 25, duct 32, and exhaust port 33. When the vehicle wheels pass off the platform 19, the latter is restored to its normal position and the valve 29 is pulled back to 40 neutral position. Inside the building is located a platform actuated valve mechanism which is a duplicate of the one hereinbefore described, but which operates in a reverse manner. Thus, when the vehicle passes over 45 the platform 34 of this mechanism inside the building, fluid pressure is admitted to the ends of the cylinder 13 through the inlets 17, and the pistons 14 are forced inward to close the doors. The fluid pressure between 50 the pistons previously admitted escapes through the exhaust port of the valve device controlled by the platform 34. When the vehicle is to be run out of the building, the left side of the platform 34 is depressed, 55 whereupon the doors are opened, and when the vehicle depresses the platform 19, the

valve 29 is pulled upward in the casing to uncover the outlet 25, whereupon fluid pressure is admitted to the cylinder ends to close the doors.

65 In connection with the door-operating mechanism, there is also provided a latch 35 for locking the doors 12. This latch is a plate having a bottom edge recess 36 in which seat keeper pins 37 when the doors are closed, and upon lifting the plate off the pins, the doors are free to slide open. The ends of the latch plate are beveled so that the plate may slip over the pins and come in holding position when the doors slide closed. 70

75 The latch 35 is carried by the stem 38 of a piston 39 working in a fluid pressure cylinder 40 obtaining its motive fluid from a connection 41 with the pipe which delivers the fluid pressure for opening the doors. Thus, 80 before the pistons 14 start to open the doors, the piston 39 is forced upward in the cylinder 40 to disengage the latch 35 from the keeper pins 37.

85 Fig. 8 shows a fluid pressure cylinder 42 having a single piston 43 connected by a rod 44 to one of a pair of swinging doors 45. The other one 46 of the doors swings with the door 45, a connection being provided 90 whereby the two doors are operated together. 95 This connection comprises a lever 47 fulcrumed at 48 on the door frame 49^a and having one end connected to the door 45, with its other end connected by a link 49 to a lever 50 fulcrumed at 51 to the door frame 95 49^a and connected to the door 46.

I claim:

A door-operating mechanism comprising a fluid pressure actuated mechanism adapted to be connected to the door to open and to close 100 the same, a valve mechanism controlling the admission of fluid pressure to the aforesaid mechanism, and vehicle-operated tiltable members connected to the valve mechanism for actuating the same, and tiltable in planes 105 parallel to the plane of the door when closed, said members being adapted to be positioned on opposite sides of the door, and each being tiltable in two directions, the tilting movement of the outer member in one direction 110 admitting fluid pressure to open the door and in the other direction admitting fluid pressure to close the door, and the tilting movement of the inside member admitting fluid pressure reversely.

115 In testimony whereof I affix my signature in the presence of two witnesses.

JOHN S. WILLIAMSON.
